UNITED STATES PATENT OFFICE.

JOHN BRAISLIN, OF BURLINGTON, NEW JERSEY.

IMPROVEMENT IN TILE-MACHINES.

Specification forming part of Letters Patent No. 40,456, dated November 3, 1863.

To all whom it may concern:

Be it known that I, JOHN BRAISLIN, of Burlington, Burlington county, New Jersey, have invented certain Improvements in Tile Machinery; and I do hereby declare the following to be a full, clear, and exact description of the same, reference being had to the accompanying drawings, and to the letters of reference marked thereon.

My invention consists of certain improvements, fully described hereinafter, in machinery for making draining and other tiles.

In order to enable others skilled in this class of machinery to make and use my invention, I will now proceed to describe its construction and operation.

On reference to the accompanying drawings, which form a part of this specification, Figure 1 is a vertical section of my improved tile-machine; Fig. 2, a front view, looking in the direction of the arrow, Fig. 1; and Fig. 3, a sectional plan on the line 1 2, Fig. 1.

Similar letters refer to similar parts throughout the several views.

A represents the base-plate of the machine, on which is erected a box, B, and at the front of the latter is the mixing-trough or reservoir C.

To the base-plate are secured the two frames D and D', one being situated on each side of the box B and mixing-trough C, and in a cross-bar, E, secured to the two frames, turns the upper end of the shaft F, the lower end of the latter turning in a step, G, secured to the bottom of the trough C. Above the cross-bars E the shaft F is cranked, and the cranked portion e of the shaft is embraced by one end of the connecting-rod H, the opposite end of which is jointed to the upper arm of the lever I, the latter having its fulcrum on a pin, J, secured to or turning in the opposite frames D and D'. The lower arm of the lever I is connected by a rod, K, to a projection, a, Fig. 3, on the cross-head L, which is arranged to slide in guides e', secured to the inside and opposite sides of the box B, the cross-head being secured by a bar, f, to the plunger M, which fits snugly, but so as to slide freely between the opposite sides of the box B and between the under side of the mixing-trough C and upper surface of the base-plate A.

The shaft F, at a point within the trough, is provided with several arms, i i, each having a

number of projections or spikes, and near its lower end the shaft is provided with an arm, j, having at its end a plate, k, so arranged that as the shaft revolves the said plate will move directly above an opening, m, which forms the communication between the mixing-trough C and the space N, in which the plunger M operates.

In front of the machine, and covering the space N, is the forming-plate P, in which are three openings, n, and into each opening projects a short cylindrical pin, q, which forms the internal diameter of the tiles manufactured by the machine, the external form being determined by that of the openings n. The pins q are secured to a bar attached to the back of the plate P, and this bar is so formed that it shall present no obstruction to the free passage of the clay through the spaces between the pins q and edges of the openings n.

At the rear of the forming-plate P, and between the latter and the mixing-reservoir, is an opening, x, large enough for the admission of a man's hand into the space N, this opening being closed by a block, y, secured to or forming a part of the bar Q, which is hinged at one end to the portion of the machine which projects beyond the mixing-reservoir, the bar to be secured at the opposite end by any suitable fastening. In the present instance the shaft is driven by horse-power, the lever R, to which the horse is harnessed, being secured to the top of the shaft. The latter, however, may be driven by belts or any suitable system of gearing.

The shaft F having been set in motion, the wet clay in the reservoir will be thoroughly mixed by the revolving spiked arms i i, while the plate k is the means of causing a portion of this wet clay to pass through the opening m into the space N every time the said plate passes above the said opening. In the meantime a reciprocating motion is imparted to the plunger through the medium of the cranked portion e of the shaft F, the rod H, lever I, and rod K. As the plunger M advances it pushes before it the clay which has passed from the mixing-reservoir through the opening m and into the space N. On the continued advance of the plunger it closes the opening m, through which no more clay can pass until the plunger retreats. There is now in advance of the plunger a sufficient quantity of clay cut

off from the supply in the mixing-reservoir for the plunger during the completion of its forward movement to force through the openings *n* in the plate *P*, and thereby convert the clay into the desired tiles. As the plunger returns and the opening *m* is exposed another supply of clay is passed into the space *N* to be converted into tiles during the repetition of a forward movement of the plunger. When there is a stone or any other obstruction at the rear of the plate *P* to prevent the free passage of the clay through the said plate, the bar *Q*, with its block *y*, is raised, so as to permit an attendant to insert his hand into the space *N* and remove the obstruction. As the continuous tubes of clay pass from the plate *P* they take their course over a series of rollers, which are common to other tile-machines, the tubes being cut to the desired lengths and subsequently dried and baked.

Although my improved machine has been illustrated as applied to the forming of tubular draining-tiles, it will be evident that it may be applied to the formation of other tiles, the shape of which must be determined by that of the openings in the plate *P*.

I wish it to be understood that I do not desire to claim of itself the forming-plate *P*, inasmuch as similar plates have been used in

other tile-machines; nor do I desire to claim separately the mixing-reservoir *C* with its spiked arms; but

I claim as my invention and desire to secure by Letters Patent—

1. The reciprocating plunger *M*, space *N*, and forming-plate *P*, in combination with a mixing-reservoir and the opening *m* at the bottom of the same, the whole being arranged and operating substantially as and for the purpose herein set forth.

2. The mixing-reservoir *C* and vertical shaft *F*, with its plate *k*, in combination with the said opening *m*.

3. The vertical cranked shaft *F*, rod *H*, lever *I*, rod *K*, and plunger *M*, the whole being arranged for joint action, substantially as set forth.

4. The opening *x* at the rear of the plate *P*, in combination with the bar *Q* and block *y* or other equivalent movable cover for the said opening.

In testimony whereof I have signed my name to this specification in the presence of two subscribing witnesses.

JOHN BRAISLIN.
